NONLOCKING BUMPER GUARD

Oscar H. Goetz, Chicago, Ill., assignor to American Chain & Cable Company, Inc., a corporation of New York

Application March 16, 1936, Serial No. 69,076

7 Claims. (Cl. 293—55)

The present invention relates to bumpers for automobiles and has for an object to provide an improved vertical guard therefor.

It is customary to provide bumpers with guards that extend vertically above and below the bumper, thereby virtually extending the depth of the protective zone of the bumper. This extension is particularly useful where two vehicles provided with bumpers come into collision, because it seldom happens that both bumpers are at exactly the same level. The guards are intended to prevent one bumper from overriding the other with resultant damage to the vehicles carrying them. However, it not infrequently happens, with guards as heretofore constructed, that a bumper will override or underride the guard of another bumper and will become hooked fast thereto. When thus interlocked, it is usually a difficult matter to disengage the bumpers.

An object of the present invention is to provide a bumper guard in which such interlocking of bumpers is prevented.

A more specific object of the invention is to provide a guard with a vertical extension which is rigid with the bumper when subjected to an inward force, that is, a force directed toward the vehicle carrying the bumper, but which is resiliently yieldable to a pull in the opposite direction. Thus, my improved guard serves all the purposes of a rigid guard as heretofore made with the advantage that it will yield in case another bumper should become hooked upon the extension and permit ready disengagement of the parts.

Another object of the invention is to provide the yieldable extension with a rounded guide surface on the inward side thereof such that when a bumper has been hooked by the extension it will be guided by such surface to clear itself from the guard.

Other objects and advantages of my invention will appear in the following description of a preferred embodiment and thereafter the novelty and scope of the invention will be pointed out in the claims.

In the accompanying drawing:

Figure 1 is a face view of my improved guard applied to a bumper, the latter being shown fragmentally;

Fig. 2 is a side elevation of the structure shown in Fig. 1, looking in the direction of the arrow 2; and

Fig. 3 is a face view of a bumper provided with a pair of my improved guards.

The bumper shown in the drawing consists of a bar 8 of concavo-convex cross-section with the

convex side facing outwardly. Mounted on this bar are two guards 10. Each guard comprises a body portion 12 suitably curved to fit against the convex face of the bar and secured thereto by a bolt 14 bearing a clamping nut 16 at the inner end thereof. The bumper is supported on the vehicle by means of resilient brackets 18 having lateral flanges 20 through which the bolts 14 are passed and against which the nuts 16 are tightly secured.

The body portion 12 of each guard is provided with ears 22 at the upper and lower ends thereof and between these ears are mounted extensions 24, one to the upper and the other to the lower end of the body. These extensions are hinged to the body by means of bolts 28 which pass through the ears 22 and through inwardly directed marginal flanges 30. The flanges are thickened as at 32 where the hinge bolts penetrate them. These flanges terminate at one of their ends adjacent the bumper in hooks or stop fingers 32 which are adapted to engage the inner face of the bumper bar 8 when the extensions are in substantially vertical position, as shown in full lines in Fig. 2. In such vertical position the extensions are maintained resiliently by means of springs 34 disposed at the inner side of the bumper, which springs are hooked to the flanges 30 at 36.

It will be noted by an inspection of Fig. 2 that the flanges 30 are formed with curved margins substantially concentric with the hinge bolts, extending thence in one direction to form the stop fingers 32 and in the opposite direction tapering off to zero at the free extremity of the extension. The flanges are thus formed to serve as guides for an opposing bumper, as will be explained hereinafter.

In operation should an opposing bumper B (Fig. 2) strike one of the extensions, it will be blocked thereby because the stop fingers 32 will prevent it from swinging inwardly. However, should the opposing bumper override and snap past an upper extension it can be readily disconnected therefrom by a direct pull, because the extension will swing outwardly on its hinge pin 22, as indicated in broken lines in Fig. 2, and the bumper B will be guided by the curved edges of the flanges 30 over the hinge connection of the extension to the guard body. Obviously, the lower extension would act in the same way in case the bumper B were low enough to ride under the bumper 8. Thus, in either case, the guard will be found to be nonlocking and self-clearing.

of my invention it will be understood that this is to be taken as illustrative and not limitative and that I reserve the right to make various changes in form, construction and arrangement of parts 5 falling within the scope of my claims.

I claim:

1. A bumper guard comprising a body portion adapted to be clamped against the outer face of a bumper, a vertical extension hinged to the 10 body and having a stop finger extending past the hinge point of the extension and adapted to bear against the inner face of the bumper when the extension is in substantially vertical position, and a spring normally holding the extension in 15 vertical position but yieldable to permit the extension to swing outwardly.

2. A bumper guard comprising a body portion adapted to be clamped against the outer face of a bumper, a vertical extension hinged to the 20 body and having a stop finger extending past the hinge point of the extension and adapted to bear against the inner face of the bumper when the extension is in substantially vertical position, and a spring normally holding the extension in 25 vertical position but yieldable to permit the extension to swing outwardly, said extension being formed on the inner side thereof with guide means to guide an object hooked to the extension clear of the hinge between the extension and body.

3. A bumper guard comprising a body adapted to be clamped to a bumper, a pair of vertical extensions, one hinged to the top and the other to the bottom of the body, each extension having 35 a stop finger extending past the hinge point and adapted to bear against the inner face of the bumper when the extension is in substantially vertical position, and spring means connecting the extensions and urging the extensions to vertical position but permitting either or both of the 40 extensions to swing outwardly in response to an outwardly directed force.

4. A bumper guard comprising a body adapted to be clamped to a bumper, a pair of vertical extensions, one hinged to the top and the other 45

to the bottom of the body, each extension having a stop finger extending past the hinge point and adapted to bear against the inner face of the bumper when the extension is in substantially vertical position, and spring means connecting 5 the extensions and urging the extensions to vertical position but permitting either or both of the extensions to swing outwardly in response to an outwardly directed force, each of the extensions being formed with a guide flange adapted 10 to guide an engaging body clear of the hinge points upon exerting a force tending to separate such body from the bumper.

5. A bumper guard comprising a body adapted to be seated against the front face of a bumper 15 bar, a vertical extension hinged to the upper end of the body, a vertical extension hinged to the lower end of the body, each extension having a portion adapted to bear against the rear face of the bumper bar when the extension is in vertical 20 position and means for holding said extensions in vertical positions and said portions pressed against the rear face of the bumper bar.

6. A bumper guard comprising a body having a recess in its rear face adapted to receive a 25 bumper bar, vertical extensions hinged to the upper and lower ends of said body at points to the rear of the front face of the bumper bar and having portions adapted to bear against the rear face of the bumper bar when said extensions 30 are in vertical position, and means for holding said extensions in vertical position.

7. A bumper guard comprising a body having a recess in its rear face adapted to receive a bumper bar, vertical extensions hinged to the upper and lower ends of said body having portions 35 adapted to bear against the rear face of the bumper bar when said extensions are in vertical position, and spring means connecting said extensions and located to the rear of said bumper 40 bar for holding said extensions in vertical position and said portions pressed against the bumper bar.
